(57) **CLAIM**

The ornamental design for a plant stand, as shown and described.

DESCRIPTION

FIG. 1 is a front elevation view of a plant stand showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a top-left perspective view thereof;

FIG. 8 is a back, right-side and bottom perspective view thereof;

FIG. 9 is a perspective view thereof, showing two layers in a different position;

FIG. 10 is a perspective view thereof, showing two layers in a different position;

FIG. 11 is a perspective view thereof, showing two layers in a different position;

FIG. 12 is a perspective view thereof, showing two layers in a different position; and,

FIG. 13 is a perspective view thereof, showing two layers in a different position.
